UNITED STATES PATENT OFFICE

109,000

DESIGN FOR A DRESS

Philip Schlessel, New York, N. Y.

Application February 2, 1938, Serial No. 74,811

Term of patent 3½ years

To all whom it may concern:

Be it known that I, Philip Schlessel, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

My design is characterized by the combination on the dress disclosed, of the strips wound in tubular formation, and attached to the dress in the arrangement shown.

I claim:

The ornamental design for a dress, substantially as shown, and described

PHILIP SCHLESSEL.
